Lawrence N. Boosey, Detroit, Mich.

Application October 21, 1943, Serial No. 111,446

Term of patent 14 years

(Cl. D91—1)

To all whom it may concern:

Be it known that I, Lawrence N. Boosey, a citizen of the United States, residing at Detroit, county of Wayne, and State of Michigan, have invented a new, original, and ornamental Design for a Combined Valve and Vacuum Breaker for Water Systems, of which the following is a specification, reference being had to the accompanying drawing, forming a part thereof.

The figure is a perspective view of a combined

valve and vacuum breaker for water systems showing my new design.

The side of the article not shown in the figure is substantially like the side shown.

I claim:

The ornamental design for a combined valve and vacuum breaker for water systems, substantially as shown.

LAWRENCE N. BOOSEY.
